(74) Attorney, Agent, or Firm — Burr & Forman, LLP

(57) **CLAIM**

The ornamental design for the soldering iron handle, as shown and described.

DESCRIPTION

FIG. 1 is a perspective view of a soldering iron handle of a soldering iron in accordance with an embodiment of the present invention;

FIG. 2 is a top view of the soldering iron handle of FIG. 1; FIG. 3 is a bottom view of the soldering iron handle of FIG. 1;

FIG. 4 is a right side view of the soldering iron handle of FIG. 1;

FIG. 5 is a left side view of the soldering iron handle of FIG. 1;

FIG. 6 is a rear view of the soldering iron handle of FIG. 1; and,

FIG. 7 is a front view of the soldering iron handle of FIG. 1.

The broken lines of the soldering iron handle in FIGS. 1-7 are illustrative of portions of the soldering iron handle that form no part of the claimed design.

1 Claim, 6 Drawing Sheets(56)
